UNITED STATES PATENT OFFICE.

JONATHAN C. MELOON, OF PROVIDENCE, RHODE ISLAND, ASSIGNOR TO GENERAL FIRE EXTINGUISHER COMPANY, OF PROVIDENCE, RHODE ISLAND, A CORPORATION OF NEW YORK.

PIPE-CO尤PLING.

1,299,371.

Specification of Letters Patent.

Patented Apr. 1, 1919.

Application filed January 2, 1918. Serial No. 209,885.

To all whom it may concern:

Be it known that I, JONATHAN C. MELOON, a citizen of the United States, residing at Providence, in the county of Providence and State of Rhode Island, have invented new and useful Improvements in Pipe-Couplings, of which the following is a specification.

This invention relates to improvements in pipe couplings.

In office buildings which rise above the height that can be reached by fire fighting forces from the street, it is necessary to maintain stand-pipes with outlets for connections with hose on the upper floors. Brass couplings are used, because of the necessity of so providing that the parts shall not stick together when needed for use. The maintenance of these connections in proper working order is the occasion of considerable expense for labor of inspection and for replacement of stolen parts. Experience has shown that thieves make a regular practice of removing the coupling including attached hose in order to melt them or by other means to recover the value of metal in them. Through a period of years, no effective preventive has been discovered, because the devices which such persons may adopt, to make their presence in the building and their handling of the fire prevention apparatus seem proper and authorized, are too easily successful. A considerable number of buildings are thus robbed every week, with resulting derangement of the fire extinguishing apparatus and great danger to the building in case fire breaks out, as well as with incidental cost of replacement of parts, and extra cost of inspection to discover such losses.

It is a particular object of the present invention to prevent thieving of this sort. The invention is, however, applicable to couplings used in other locations, as between lengths of hose, and in other places where pipe couplings are employed; and it has other advantages as it reduces the cost of non-sticking couplings very considerably.

The objects of the invention are accomplished by eliminating from the coupling the brass which is the incentive for theft. As the size and strength of the parts can not be materially reduced from that hitherto in use, and no material cheaper than brass is known, of which the coupling as a whole

can be made, the invention accomplishes the desired end by making a construction and combination of parts in which the major portion of the coupling is of a cheaper material, and one of the elements of the coupling is a composite structure including an interior small portion of brass suitably located. Specifically, the material which it is preferred to use is iron, for the main body of both coupling members. This comprises the whole of the male member of the coupling and comprises nearly the whole of the female member; but the latter is made of three separable pieces, one being the customary swivel piece which is adapted to screw upon the male member, another being a nipple or end therefor adapted to be attached to the hose or other piece which is to be coupled, and the third being a piece of brass mechanically interlocked with and surrounded by these two, and serving to join them. The brass constitutes the portion of the female member on which the swivel part is mounted irremovably and on which it turns, and affords surfaces facing against all contacting surfaces of the swivel so that none of the latter rub against any iron on the female member. The result is a coupling having the necessary mechanical and structural features of the couplings hitherto in common use, yet devoid of the metal value which constitutes the incentive for theft of the same.

In the accompanying drawings, which illustrate an embodiment of the invention:—

Fig. 1 is a side elevation of a stand pipe with outlet and hose;

Fig. 2 is a medial, longitudinal section through a coupling, with the parts ready to go together;

Fig. 3 is a similar section through one of the pieces thereof at a preliminary stage of manufacture; and

Fig. 4 is a transverse section at 4—4 through a fragment of Fig. 2.

Referring to the drawings, 10 indicates a stand pipe, having a branch outlet closed by a valve whose discharge pipe 11 constitutes one member of a coupling for a hose pipe. This member has a screw-threaded portion 12 upon which the other member of the coupling fits, and terminates in the usual annular surface 13 against which an annular packing 14 is pressed by the other member of the coupling. The

2

member 11, which is portrayed as the male member of the coupling, may be a tubular piece of any ordinary or suitable size and shape and is made of inexpensive, non-rusting material such as galvanized or malleable iron, having an external thread to engage the female member of the coupling. The latter consists of the swivel tube 17; the base tube, or end, 15, of the coupling, and a connecting tube or thimble 18, all of similarly inexpensive material, such as galvanized iron, except the thimble 18. The base tube 15 is represented as adapted to be permanently attached to a line of hose, and for this purpose has internal corrugations 16, against which the hose can be expanded and held by an internal brass ring 16'. The swivel has the usual thread adapted to engage the threaded portion 12 of the male member of the coupling, to be readily screwed on and off in order to make and unmake the coupling. By cutting these threads a little too deeply for ordinary fitting and then applying a galvanized coating they can be made smooth enough and of proper size to perform their functions as threads adequately, without adhering to each other. The swivel tube 17 has the projecting pins 19, diametrically opposite each other, adapted to be engaged and turned by a spanner; or has other suitable means by which this piece can be turned upon the screw threads 12 of the other member of the coupling. The connecting piece or thimble 18 is a ring mounted internally and adapted to be arranged between the two pieces 15 and 17 of the female member of the coupling, separating them from each other and at the same time holding them together, and also constituting the compression member which seats the washer or other packing 14 upon the end 13 of the male member 11. As this piece 18 is preferably made of brass, and the piece 15 is of galvanized iron, means is provided to attach these two together consisting of a screw thread 20 cut on the inside of the base tube 15 and on the outside of the connecting tube 18; and the latter has a flange 21 extending straight out and adapted to be seated upon the end of said base tube 15 when the connecting tube 18 has been screwed tightly into it. When the connecting tube has thus been screwed firmly to its seat it may be secured there by a pin 26. Preferably this flange is not equal in width to the thickness of the metal of the base tube, and the latter is formed with a projecting lip 22 and its outer edge is adapted to overlie and inclose or cover the outer edge of the flange 21, when its inner face is thus seated against the end tube 15. The other face of the projecting flange 21 is adapted to engage the nearby face of the swivel tube 17. Thus it intervenes between the base tube 15 and the swivel tube

17, prevents these two galvanized iron pieces from making contact with each other, and is at the same time concealed from exterior view. The connection of the thimble 18 to the swivel 17 is made in permanent fashion. A terminal flange 23 is provided upon it, connecting a neck 24. The neck passes an inward projecting terminal flange 25 on the swivel member, and the terminal flange 23 of the thimble extends outward within the swivel tube, beyond its inward extending terminal flange 25. In order to construct this, the connecting piece 18 is made in the form marked 18' and shown in Fig. 3, where the piece is shown as having the same shape as in Fig. 2, except that the flange 23, there marked 23', stands nearer the axis, and the neck 24 stands in conical shape, being marked 24'. The elements of this cone, as represented, make an angle of about 12° with the axis. The extreme outer diameter of the flange 23' when in this position is small enough to pass through the hole through flange 25 on the swivel tube 17. The flange portion 23' of the connecting tube, being inserted into the swivel tube 17 through the end where flange 25 is, is afterward expanded by a suitable tool so that the conical neck 24' becomes cylindrical in form, as shown at 24 in Fig. 2. The thimble 18 and the swivel tube 17 are thus permanently engaged together, with a loose engagement of one flange behind the other which permits the usual action of the swivel piece.

100 The elimination of danger of adhesion of parts by rusting or otherwise is made possible by the three part construction and by the selection for the connecting piece of a homogeneous metal that is capable of being bent in the expanding process without the production of superficial cracks or other injurious developments that would render it liable to rust or stick. It will be observed that although a joint of galvanized iron can be made between the screw threads of the parts 17 and 11, because these contacting surfaces can be galvanized as separate exposed surfaces, the engaging flange 23 and neck 24 cannot be made of galvanized iron 115 with good effect.

110 The invention, consequently, makes it possible to produce what has heretofore been impossible, so far as I am aware, viz: a coupling of galvanized iron which is capable 120 of meeting the standard requirements of fire underwriters and the like as regards safety and constant readiness for use. While the new coupling is not entirely of galvanized iron, it is nevertheless true that the inserted 125 thimble of other metal is so small in size, and so secure in position that it neither adds appreciably to the cost of the material which constitutes this member of the coupling nor detracts appreciably from the strength 130

thereof; moreover, it is not visible, as an incentive for theft, and if stolen gives no worth while return for the effort and cost involved in extricating it. In consequence, 5 the invention makes possible the use of what are practically galvanized iron couplings, where formerly only couplings of much more expensive metal have been used because of the unsuitability of galvanized iron. 10 Thereby it puts an end to the thievery of coupling members from stand-pipes and the like, against which thus far no adequate means of protection has been found, and so enhances the security against fire in the 15 down-town office buildings of large cities and at the same time notably reduces the cost of the constant inspection needed to maintain not only the degree of security which has heretofore been had, but the enhanced security which the use of the invention affords.

While the invention is illustrated as it may be applied to a screw coupling, it may be applied to couplings in which a different 25 method of fastening is used.

The screw method is also illustrated as the means employed to provide a firm joint without leakage of water between the base tube 15 and the connecting tube 18. It has 30 been found by experience that no washer or packing is needed between the flange 21 of the latter and the end surface of the base tube 15 upon which this flange is seated; but it is obvious that such packing might 35 be inserted if desired, or that other means might be employed for making the connecting tube fast with a water-tight joint within the base tube.

I claim as my invention:—

40 1. A pipe coupling one of whose members comprises a base tube, a swivel tube and a connecting tube; the connecting tube having an unstretched metal portion fast to the base tube, and the swivel tube being mounted on 45 the connecting tube and adapted to be secured to the other member of the coupling and thereby to hold the two members of the coupling tightly together; the said connecting tube being made of material of a nature 50 not to adhere to the swivel by corrosion or the like and having a part preventing contact between said base and swivel.

55 2. A pipe coupling having a member comprising a base tube, a connecting tube fast to the base tube, and a swivel tube mounted on the connecting tube and adapted to be secured to the other member of the coupling and thereby to hold the two members of the coupling tightly together, the said connect-

ing tube having an unstretched metal portion 60 fast to the base tube and being made of non-corrodible material, the said base and swivel being made of iron, and there being non-corrodible material intervening and preventing contact between the swivel and the base. 65

3. A pipe coupling having a member comprising a base tube, a connecting tube fast to the base tube, and a swivel tube mounted on the connecting tube and adapted to be secured to the other member of the coupling 70 and thereby to hold the two members of the coupling tightly together, the said connecting tube being arranged internally of and unstretched within the base tube and having two external ridges, one of which projects 75 between the base and the swivel tubes and the other of which projects within the swivel tube and is too large to come out, and being made of material different from that of the swivel and of a nature not to adhere thereto, 80 and the said base and swivel being made of relatively inexpensive material.

4. A pipe coupling having a member comprising a base tube, a connecting tube, and a swivel tube mounted on the connecting 85 tube and adapted to be secured to the other member of the coupling and thereby to hold the two members of the coupling tightly together, the said connecting tube having a screw threaded water-tight joint with the 90 base tube and a head expanded into the swivel tube, and an intervening part separating the swivel from the base, and being made of material different from and of a nature not to adhere to that of the swivel; 95 the said base and swivel being made of relatively inexpensive material.

5. A pipe coupling having a member comprising a base tube, a connecting tube, fast to the base tube, and a swivel tube mounted 100 on the connecting tube and adapted to be secured to the other member of the coupling and thereby to hold the two members of the coupling tightly together; the said connecting tube being screwed unstretched into the 105 base tube and having externally thereof two flanges of larger diameter than the swivel, one of which is engaged and concealed within it and the other of which is outside it; and there being an annular lip of the base 110 tube surrounding said outside flange; the said base and swivel being made of relatively inexpensive material, and the said connecting tube being made of different material of a nature not to adhere thereto. 115
